Primary Examiner — Keli L Hill(74) *Attorney, Agent, or Firm* — Oppedahl Patent Law Firm LLC**(57) CLAIM**

The ornamental design for a virtual reality headset, as shown and described.

DESCRIPTION

FIG. 1 is a front view of an all-in-one computer showing the new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is another perspective view thereof; and,

FIG. 9 is a alternate perspective view thereof.

1 Claim, 9 Drawing Sheets(56)
